UNITED STATES PATENT OFFICE.

OSCAR EARNEST PUTTY, OF SAN PEDRO, CALIFORNIA.

OVERSTUFFED BED DAVENPORT.

Application filed June 16, 1925. Serial No. 37,451.

My invention relates to davenports, and more particularly to davenports which are adapted to serve both as a bed and as a seat.

It accordingly is an object of my invention to provide a novel form of bed davenport comprising two relatively movable members, one comprising a partly upholstered back member equipped with a set of stop elements, and a pair of upholstered arms having end members, which end members have associated therewith a set of tracks and supporting brackets, which stop elements, tracks and brackets are adapted to coact with a removable and extensible combined seat and bed device or member, which device or member may be folded or extended alternatively to serve as a seat or a bed, provision being made in said device or member whereby either a mattress, bed clothing and pillows, or upholstery, may be housed therein, to support said device or member either in folded or extended position, for preventing the collapse thereof, irrespective of any movements of the individuals occupying said davenport, there being means also associated with said davenport whereby injury may effectively be prevented to rugs or floors.

Another object of my invention is to provide a novel form of detachable and extensible combined bed and seat device to be associated with my davenport, with a novel form of hinge especially adapted and constructed for use in connection with said device, provision being made to prevent said hinge from collapsing when said device is in extended position.

It is also within the province of my invention to equip my novel seat and bed device with sets of collapsible members comprising at least two members adapted to be superimposed, at least one intermediate member being associated by means of a novel form of hinge with said members, there being a set of floating axles associated with said intermediate member whereby said device may be supported and positively locked against all movements in both positions.

Another object of my invention is to provide a combined detachable upholstery member having hingedly associated therewith a floating pad adapted to be resiliently mounted on my novel form of seat and bed device, said pad being held taut when said device is in collapsed or folded position, and is held floating when said device is extended.

It is also an object of my invention to provide a novel form of bed davenport which is simple in construction, easy and inexpensive to manufacture, durable, thoroughly reliable and efficient in operation, practically impossible to get out of order, composed of a minimum number of parts, and one which will thoroughly and reliably effect the objects intended.

Further objects and advantages of my invention will become more apparent as the description thereof proceeds.

Reference is had to the accompanying drawings in which similar reference characters denote similar parts. In the drawings,

Fig. 1 is a front elevational view of the back member of my improved bed davenport,

Fig. 2 is an enlarged end elevation of the combined seat and bed member or device adapted to be detachably associated or extended from the back member shown in Fig. 1, to alternatively form a seat or bed, said figure being drawn on a much enlarged scale from that shown in Fig. 1,

Fig. 3 is an inside elevational view of the end portions of the back member,

Fig. 4 is an end elevational view of the combined seat and bed member or device, shown in extended position,

Fig. 5 is a fragmentary top plan view of Fig. 4,

Fig. 6 is a fragmentary detail perspective view of one of the bars or legs associated with my combined seat and bed device,

Fig. 7 is a detail sectional view of one form of floating axle,

Fig. 8 is a detail perspective view of one of the hinge joints, said figure being drawn on a much enlarged scale from that shown in Fig. 1,

Fig. 9 is a similar view, but on a very much enlarged scale, of one of the locking and supporting brackets, said figure being drawn on a much enlarged scale from that shown in Fig. 1,

Fig. 10 is a detail elevational view showing in exaggerated form the manner in which certain of the cushioning members or springs may be secured to the angle irons,

Fig. 11 is a fragmentary detail perspective view illustrating the manner in which one of the upholstery members may be detachably mounted on the seat and bed device,

Fig. 12 is a fragmentary detail elevational view showing the manner in which two sets of

resilient or spring members may be associated with each other and with the angle irons of my seat and bed device.

Fig. 13 is an end view of the davenport, one end and the rear portion removed, showing the combined seat and bed member in the position it assumes when collapsed and pushed into the back member.

Fig. 14 is a similar view showing the combined seat and bed member extended, and

Fig. 15 is a modified form of the joint depicted in Fig. 8.

Describing my invention more in detail, the back member of my improved davenport comprises a frame, shaped as shown in Fig. 1, and equipped with any suitable form of overstuffed or other upholstery S, and also provided with a pair of upholstered arms or end portions, said back member being provided with suitable castors, mounted in any preferred manner, to enable said back member to be moved about on floors or rugs without damaging the same.

As will be seen from Fig. 1, the lower portion of the back member is plain, and is equipped with a set of stop elements 2 of any desired form and made of any preferred material, either integral with said back member or secured thereto in any desired manner, the purpose of which will presently be explained.

Each end portion of the back member on its plain portion is equipped with a track T of any suitable form, preferably, though not necessarily, in the form of an angle iron, and secured to the end pieces by riveting or otherwise. Said tracks, the purpose of which will presently be explained, may extend the entire length of said end pieces, or only part way, as shown, and may be positioned above the floor at any convenient distance, so long as said tracks will coact with certain other elements of my device, hereinafter more particularly explained.

Each end portion of the back member, as shown in Fig. 1, is also equipped with a supporting bracket and locking element 1, shown on a very much enlarged scale in Fig. 9. The bracket 1 is provided with a pair of end securing members whereby it may be secured to the ends portions of the back member, and has cut-away portions 6 and 7 of comparatively deep and shallow configuration to accommodate the floating axle or bolt 3, either integral with or secured to one of the parts of my device in any desired manner, as presently to be more fully explained. The axle 3 is equipped with a head 4, and if desired, said head may be cut away as more particularly shown in Fig. 7 at 5, though this cut-away portion is not essential, as the head 4 may be entirely round and still function in the manner presently to be described.

The bracket 1 is also formed with an up-

standing projection 8 to coact with the floating axle 3 to form a positive lock to prevent any movement of the device, irrespective of any movement of the individuals occupying the davenport, either as a seat or a bed. It will of course be understood that the form of the cut-away portions 6 and 7 as well as that of the projection 8 may be any that in practise may suggest itself. It is also clear that the bracket 1 may be constructed of any material preferred.

The combined seat and bed member adapted to be detachably and extensibly associated with the back member of my davenport is shown in Figs. 2, 4 and 5, and preferably comprises three main members, two outside members, adapted to be superimposed, and an intermediate member, hinged to each of said members in a manner presently to be described, one of said outer members being of a greater length than the other.

The seat and bed member or device is constructed of a frame-work composed of angle irons, riveted together and equipped with especially constructed hinges, the members 16 and 17, as well as the intermediate member, being provided with spiral and chain or link springs of any preferred type, and mounted thereon in a manner presently to be described. Of course, it is to be distinctly understood that I do not desire to be limited to just three such members, as in practise the number may be varied, so long as said members may be folded or superimposed, and so fashioned that either upholstery or bed clothing, including mattress as well as pillows may be housed therebetween.

As shown in Figs. 2 and 4, the members 16 and 17 are equipped with any suitable form of lattice work, associated with the angle irons of said members in any preferred way, to prevent the mattress and bed clothing from coming in contact with the movable parts of the device and thus getting caught and torn.

As shown in Figs. 2, 4 and 11, the seat and bed device is provided with an upholstery member 29, detachably associated with the intermediate member by means of cross bars 32, clamped in position by means of wing nuts 33, or other fastening devices 33, the upholstery member 29 being adapted to be removed from the framework of the intermediate member simply by unscrewing the wing nuts 33 and swinging the bars 32 away from the angle irons.

As shown more particularly in Fig. 4, a floating pad or upholstery member 30 is hingedly associated with the member 29, which member forms the front upholstered portion of the davenport when assembled as a seat. The pad 30 is mounted upon a rigid frame, preferably rectangular in shape, a set of rods, if desired, being provided for this purpose, and as shown in Fig. 4, one length

of this pad is equipped with a resilient means in the shape of a set of spiral springs 38 to be attached to the lower angle iron of the member 16, said pad 30, as shown in Fig. 4, being loose when the device is extended, and taut when the device is folded, the spiral springs forming an efficient cushioning means for the seat.

Preferably, though not necessarily, I use twenty four of the spiral springs 36, as indicated in Fig. 5, and more particularly shown in Fig. 12. Said springs I preferably arrange in sets of four, though this feature is immaterial. It will be clear also that the number as well as the type of springs used may be varied as desired.

The specific manner of securing the springs 36 in place on the angle irons is shown in exaggerated form in Fig. 10. In said figure a lower spring holding bar 34 is passed over the lower turn of the spring 36, and under the innermost portion of said turn, across the space between the angle irons, as shown in Fig. 5, under the lowermost turn of the opposite spring, and above said turn on the other side, each end of said bar abutting against the side of the angle iron. An upper spring holding bar 35 is then placed over the bar 34, overlapping the slightly upturned portions of the lower turns of the springs 36, and then secured in position by means of a bolt or other securing means. Of course it will be clear that I do not propose to be limited to this specific manner of mounting the springs 36 on the angle irons, since in practice this may be varied as preferred.

A very important feature of my invention resides in the specific manner in which the members 16 and 17 are hinged to the intermediate member. It will be clear that unless a proper form of hinge is provided, the member 16 when superimposed on the member 17, will cause a binding action therebetween so that said member 16 will not seat properly on the member 17, and in fact it may not be able even to swing one member over the other.

For this purpose I have devised and constructed the especial hinged joint shown more particularly in Fig. 8, which in practice operates exceedingly well. In said figure the angle iron 13 is positioned in overlapping relation with the angle irons 10 and 12 associated with the members 17 and 16 respectively. As seen in said figure the vertical portion 11 of the angle iron of the intermediate member overlaps the vertical portions of the angle irons 10 and 12, the horizontal portion of the angle iron 11, as indicated at 14 extending over the horizontal portion of the angle iron 12 to a greater length than said angle iron 13 extends over the angle iron 10, said angle iron 11 being cut away as at 15 to provide a space to accommodate the angle iron 12 as the member 16 is being superimposed over the member 17, the angle iron 11 being

pivoted to the angle irons 10 and 12 as clearly shown in Fig. 8. If desired also, a suitable additional angle iron A', or a pair of such angle irons, as shown in Fig. 15, may be riveted to the angle irons 10' and 12', pivoted to the part 13' of the angle iron 11', which part has an overlapping portion 14', to provide a supporting means, or a reinforcing means, to insure that the hinge joint or joints will not collapse under excessive weight. In certain cases this reinforcement may not be needed.

It will be of course understood that each end of the intermediate member is equipped with the hinged joint just described as shown in Fig. 5. The intermediate member is also equipped at each end, as shown in Figs. 2, 4, and 5, with a cross bar or bracing element 28, preferably, though not necessarily riveted to said intermediate member. Of course, it is to be understood that if desired the cross bar 28 may be formed integral with the angle irons making up said intermediate member or it may be detachably secured thereto, if such a feature is found in practice to be desirable. Preferably integral with the cross bar 28 is the axle 3, hereinbefore more particularly described, which axle may be welded to the bar 28 or formed integral therewith, or associated therewith in any other manner desired. And while I have shown said axle as positioned substantially in the middle part of said cross bar, it is to be understood that if in practice it is found expedient to position the same at a different point, I reserve the right to place said axle in such position.

As shown in Figs. 2, 4, 5, 13 and 14, the angle irons associated with the member 17 are equipped with extensions 18 adapted, when the seat and bed member is extended, said extensions 18 will coat with the stop elements 2 to prevent collapse of said seat and bed member. See Fig. 14.

The member 17 is equipped with a cross bar 24 associated with said member in any preferred manner, either integral therewith or riveted thereto, as shown, and to said cross bar is pivoted, as more particularly shown in Figs. 2 and 4, a leg 22 equipped with any preferred form of anti-friction or other roller 23, which roller is adapted to engage the track T. It will of course be understood that both ends of the member 17 are provided with a construction just described. See Fig. 5. If desired also, the member 17 may be equipped with any suitable form of buffer means 25 for engagement with the member 16. A side bar or brace 27 is pivoted to the leg 22 and also to one of the angle irons of the intermediate members to form a means 125 for extending and bracing the leg 22.

A somewhat similar construction is provided on the other side of the device and with the member 16, a pivoted leg 19 equipped with a stop 21, either on one edge or on the

flat side of said leg, to prevent said leg from extending too far behind the side bar or brace 26 pivoted to the leg 19 and to the intermediate member, when the device is collapsed as shown in Fig. 2. Attention is also directed to the fact that both ends of the device are equipped with the construction just described. It should also be stated that where necessary the braces 26 and 27, and the other bars are offset or curved substantially as shown at 9 in Fig. 6, so that said bars may readily pass each other when the seat and bed device is collapsed.

If desired also the legs 19 may be equipped with a suitable buffer member or roller 20 functioning to prevent any damage to rugs or floors.

The members 16 and 17 are equipped with suitable springs, preferably, though not necessarily, in the form of wire link, chain or woven springs 37, secured to the angle irons of said members by any preferred type of coiled springs 38. Said springs, together with the springs 36, function to support the mattress forming the bed, which mattress may be tied in place by suitable tabs associated therewith, or said mattress may be entirely omitted and the inner part of the seat and bed member may be upholstered. Attention is directed to the fact that the springs 37 shown in Fig. 5 will extend entirely across the device, said springs being broken away for the sake of clearness. As shown in said figure also the bed and seat device is equipped with a set of castors 31 associated in any preferred manner with the angle iron so that said device may be moved about on floors and rugs without any damage thereto.

In operation, when the combined seat and bed member is in engagement with the back member, the extensions 18 will be positioned below and out of engagement with the stops 2, said member resting on the floor on the castors 31, so that said member may be readily pulled out without the exertion of much strength, and at the same time forming a rigid seat. See Fig. 13. Said device will of course be collapsed as shown in Fig. 2, the upholstery 29 effectually hiding any of the mechanical elements of said device, and on top of said device will be placed upholstered cushions, fitting nicely into and over the member 16, or a long upholstered member may be placed thereover, forming a complete davenport.

When it is desired to use the davenport as a bed, the cushions or upholstery members positioned on top of the member 16 are removed. The seat and bed device is then pulled out, the castors 31 effectually preventing any damage to rugs or floors. The member 16 is then unfolded from above the member 17, the various side parts and legs as well as the especially constructed joints shown in Fig. 8, readily permitting this feature. As the mem-

ber 16 is lifted from the member 17, the legs 22 will drop and assume a vertical position, the rollers 23 engaging the tracks T and the axles 3 dropping into engagement with the brackets 1 and rolling along the length thereof until said axles are in engagement with the cavity 6. (See Fig. 9). When the device is extended, as shown in Figs. 4, 5 and 14, the legs 19 will be vertical and in engagement with the floor. In pulling out the extended member, should the axles 3 be accidentally removed from the cavity 6, said axles will enter the depressions 7 and be effectively prevented from removal from the brackets 1 by the anchoring means 8. The extended member is then pushed back until said axles automatically snap into the cavities 6, the extensions 18 being then positioned under the stop 2, thus effectively preventing any collapse when the bed is occupied.

As has been made clear, when the device is folded as shown in Fig. 2, the bed clothing, including covers and pillows, or the upholstery, if used, will be completely inclosed, the wire netting, cane, or lattice work effectively preventing any of said bed clothing from being caught in the movable elements of the device, the pad 30 being held taut, but with all resiliency mounted by reason of the spiral springs associated therewith. But when the device is opened up and extended, as shown in Figs. 4, 5 and 14, the pad 30 is loosely held in position.

Attention is also directed to the fact that in view of the ease with which my improved davenport is assembled or disassembled, the frailest person will not experience the slightest difficulty in operating the same.

While I have thus described my invention with great particularity, it will be clear that the same be modified throughout a wide range. I therefore do not propose to be limited to the exact details of construction shown and described, but reserve the right in practice to make any and all modifications thereof that fall within the scope of the appended claims.

I claim as my invention:

1. In a bed davenport, in combination, an upholstered back member, said back member comprising an upholstered top portion, a plain portion extending therefrom, a pair of upholstered arms extending from said back portion, a pair of stop elements positioned on said plain portion, a pair of tracks positioned on said arms, a combined locking and supporting bracket also positioned on each of said arms, and a combined extensible and collapsible seat and bed member associated with said back member, said combined seat and bed member being equipped with stop bars coacting with said stop elements, sets of collapsible legs associated with said seat and bed member to support the same when in extended position, certain of said

- legs being coacting with said tracks to assist in supporting said seat and bed member when said davenport is in extended position, and means associated with said seat and bed member coacting with said brackets for supporting and preventing said seat and bed member from movement when said bed member is extended.
2. A bed davenport in which an extensible member is adapted to be pulled out from a back member and unfolded to form a bed, said extensible member being equipped with an upholstered element to form the front of the seat of said davenport, there being an upholstery or mattress and bed clothing supporting element rigidly associated with said upholstered element, and detachably and resiliently associated with said extensible member, whereby said supporting element may be held taut when said davenport serves as a seat, or may float when said extensible member is extended.
3. In a bed davenport, in combination, a back member comprising an upholstered back portion and a pair of upholstered arms extending therefrom, a pair of stops on said back portion, a bracket on each of said arms, a track on each of said arms positioned below said bracket, and a collapsible and extensible combined seat and bed member comprising an inner section, an intermediate section and an outer section hinged together, a pair of extensions on the lower portion of said inner section, an axle on each end of said intermediate section, a set of collapsible legs pivoted to each of said inner and outer sections, said outer section, when said member is collapsed, being superposed over said inner section, and when said member is extended said axles being positioned on said brackets, the lower end of each leg on said inner member being positioned on said tracks, and said extensions positioned under each of said stops.
4. In a bed davenport, in combination, an upholstered back portion, upholstered arms extending therefrom, a pair of stops on said back portion, a track positioned on the lower part of each of said arms, a combined support and anchoring device positioned on each of said arms and at a substantial distance below said stops, a combined seat and bed member, distinct and separate from said back portion and arms, and unconnected thereto, said member comprising a set of sections hinged together and adapted to be folded and unfolded, a pair of collapsible legs on said member for supporting the outer portion of said member when unfolded, a pair of collapsible legs engaging with said tracks when said member is unfolded, said last named legs being out of engagement with said tracks when said member is folded, a pair of extensions on one of said sections engaging with said stops when said member is unfolded, and means on one of said sections supported by and anchored to said anchoring and supporting means when said member is unfolded.
5. In a combined seat and bed member for a bed davenport, in combination, two outer mattress and bed clothing or upholstery supporting sections, an intermediate section hinged to said sections, said sections being adapted to be folded and unfolded, one of said outer sections, when said member is folded, being adapted to function as a seat, an upholstered portion, a set of pivoted bars on said portion whereby the latter may be detachably positioned on said intermediate section, springs positioned on each of said sections, and sets of collapsible legs associated with said sections whereby said member may be supported in unfolded position.
6. A combined seat and bed device for use in connection with a bed davenport, a pair of outer sections and an intermediate section hinged together so that said sections may be folded or unfolded, collapsible legs pivoted to said outer sections for supporting said member when unfolded, a pad connected to said intermediate section at one end and resilient means for connecting the other end of said pad to one of said outer sections, said pad when said device is unfolded being loose and taut when said device is folded.
7. A bracket adapted for special use in connection with a bed davenport comprising a supporting member, a pair of extensions on said member whereby said bracket may be secured to said davenport, said supporting member being provided with comparatively shallow and deep grooves, and an upwardly extending projection on one end of said member, said grooves being adapted to hold the axle on a seat and bed device associated with said davenport when said device is in extended position, said projection being adapted to prevent the accidental removal from said bracket and consequent collapse of said device when occupied.

In testimony whereof I have signed my name to this specification.

OSCAR EARNEST PUTTY.
